(57) **CLAIM**

We claim the ornamental design for a flat wall-mounted fire place, as shown and described.

DESCRIPTION

FIG. 1 is a perspective view of a first embodiment of a flat wall-mounted fire place embodying our new design;

FIG. 2 is a perspective view of a flat wall-mounted fire place of FIG. 1 with the door partially opened;

FIG. 3 is a front elevational view of FIG. 1;

FIG. 4 is a left side elevational view of FIG. 1;

FIG. 5 is a right side elevational view of FIG. 1;

FIG. 6 is a top plan view of FIG. 1;

FIG. 7 is a bottom plan view of FIG. 1;

FIG. 8 is a perspective view of a second embodiment of a flat wall-mounted fire place embodying our new design;

FIG. 9 is a perspective view of the flat wall-mounted fire place of FIG. 8 with the door partially opened;

FIG. 10 is a front elevational view of FIG. 8;

FIG. 11 is a left side elevational view of FIG. 8;

FIG. 12 is a right side elevational view of FIG. 8;

FIG. 13 is a top plan view of FIG. 8; and,

FIG. 14 is a bottom plan view of FIG. 8.

The rear view of the flat wall-mounted fire place does not form any part of the claimed design.

The broken lines shown in the drawings are for illustrative purposes only and form no part of the claimed design.
